ABSTRACT

Hand operating device for drawing a line having an elongated hollow holder adapted to be gripped by the hand of an operator for the line drawing operation, an ink tank provided in the holder and a rotatable applicator roller mounted at one end of the holder adapted to receive ink from the ink tank onto the periphery thereof while the applicator roller is rollingly contacted with a sheet so as to draw a line thereon with the holder held in upstanding position with the applicator roller positioned at the lowermost position. The ink tank is freely shiftably located in the holder so that the ink tank is urged against the applicator roller under an appropriate contact pressure by the action of gravity of the ink tank when the holder is held in the upstanding position for the line drawing operation thereby insuring an appropriate amount of ink to be supplied to the periphery of the rotating applicator roller so as to permit a correct and accurate line to be drawn on the sheet, and the applicator roller is rotatably supported by a cantilever shaft mounted on the holder thereby facilitating the guiding of the applicator roller by a rule with which the free end of the cantilever shaft is slidingly contacted so as to permit a line to be drawn in accurate position on the sheet. When the holder is maintained in the inverted upright position when the device is not used, the ink tank moves apart from the applicator roller so that the sticking of ink on the periphery of the applicator roller is positively avoided.

HAND OPERATING DEVICE FOR DRAWING A LINE

BACKGROUND OF THE INVENTION

The present invention relates to a hand operating device for drawing a line on a sheet and, more particularly, to a device of the type described above having an elongated hollow holder adapted to be gripped by the hand of an operator for the line drawing operation, an ink supplying tank provided in the holder and a applicator roller rotatably mounted on one end of the holder and adapted to be supplied with ink from the ink tank and rollingly contact with the sheet so that a line is drawn on the sheet by the rolling contact of the applicator roller with the sheet, the applicator roller being detachably mounted on the holder so that various forms of lines such as solid line, a broken line and a chain line can be drawn on the sheet by interchangeably mounting a selected applicator roller of the desired form on the holder.

Heretofore, various devices for drawing a line have been proposed. However, the prior art devices for drawing a line have various disadvantages in that they have exteriorly projected portions on the outer surface of the holder thereby making the manipulation of the device inconvenient, or the construction of the devices is very complicated thereby making the production cost high, or accurate and uniform lines can not be drawn by the prior art devices due to defective operation thereof.

The present invention aims at avoiding the above described disadvantages of the prior art devices for drawing a line.

SUMMARY OF THE INVENTION

The object of the present invention is to provide a novel and useful device for drawing a line which is simple in construction and inexpensive in manufacture and by which an accurate and uniform line can be drawn on a sheet, while the manipulation of the device is made very easy.

The above object is achieved in accordance with the characteristic feature of the present invention by providing a device for drawing a line having an elongated hollow holder adapted to be gripped by the hand of an operator for the line drawing operation, an ink tank provided in the holder and having an ink supplying portion at one end thereof and a applicator roller adapted to be supplied with ink onto the periphery thereof from the ink supplying portion of the ink tank and rotatably mounted on one end of the holder for rollingly contacting with a sheet on which a line is to be drawn when the holder is held in upright position with the applicator roller positioned at the lowermost position so that a line is drawn by the rolling contact of the applicator roller with the sheet, the device being characterized in that the ink tank is freely shiftably supported in the holder along the longitudinal axis thereof so that the ink supplying portion of the ink tank slidably contacts with the periphery of the applicator roller by the action of gravity of the ink tank thereby permitting an appropriate amount of ink to be supplied from the ink supplying portion of the ink tank onto the periphery of the applicator roller when the same is rollingly contacted with the sheet, and that the applicator roller is rotatably supported by a cantilever shaft mounted at its proximal

end on one end of the holder so that the line drawing operation is facilitated by using a rule which is slidingly contacted with the free end of the cantilever shaft.

In accordance with a further feature of the present invention, a rotatable ink roller is provided within the holder between the ink supplying portion of the ink tank and the applicator roller, which is shiftably supported in the holder along the longitudinal axis thereof and urged by a spring toward the applicator roller so that the ink roller is rollingly contacted with the applicator roller under an appropriate contact pressure therebetween afforded by the spring as the applicator roller is rotated during the line drawing operation thereby permitting an appropriate amount of ink to be uniformly supplied from the periphery of the ink roller to the periphery of the applicator roller, while the ink roller is slidingly contacted at its periphery with the ink supplying portion of the ink tank by virtue of the contact pressure therebetween applied by the action of gravity of the ink tank during the line drawing operation thereby permitting an appropriate amount of ink to be supplied from the ink supplying portion to the periphery of the ink roller while the same is rotated by the applicator roller rollingly contacting with the sheet during the line drawing operation so that an accurate and uniform line can be drawn on the sheet.

In accordance with a still further feature of the present invention, the ink roller is urged by the spring so as to be axially shifted within a predetermined range, and the cantilever shaft of the applicator roller is axially shiftably supported on the end of the holder and urged by a further spring away from the ink roller within a predetermined range so that the applicator roller is normally held apart from the ink roller thereby positively preventing ink from sticking on the portion of the periphery of the applicator roller at which the applicator roller would be contacted with the ink roller if such a further spring were not provided, the applicator roller being urged against the ink roller against the action of the further spring when the applicator roller is rollingly contacted with the sheet for the line drawing operation so that the contact pressure is held therebetween afforded by the spring which urges the ink roller toward the applicator roller thereby insuring an appropriate amount of ink to be supplied to the ink roller and an accurate line to be drawn on the sheet by virtue of the fact that the sticking of ink on the periphery of the applicator roller is positively avoided by normally maintaining the applicator roller in spaced relationship from the ink roller during the time the device is not used.

The free end of the cantilever shaft may be provided with a flattened head of enlarged diameter so as to facilitate the guiding of the device by a rule with which the flattened head of the cantilever shaft is slidingly contacted.

Further, the axis of the cantilever shaft may be offset from the longitudinal axis of the holder so as to facilitate the guiding of the device on the sheet by means of a rule.

The applicator roller may be made detachable from the holder so that various forms of lines such as a solid line, a broken line and a chain line can be drawn by interchangeably mounting a selected applicator roller of the desired form on the holder.

BRIEF DESCRIPTION OF THE DRAWINGS

FIG. 1 is a longitudinal sectional view partly broken away showing a first embodiment of the device for

drawing a line constructed in accordance with the present invention;

FIG. 2 is an end view showing the arrangement of the applicator roller of the device of FIG. 1;

FIG. 3 is a fragmentary longitudinal sectional view showing a modification of FIG. 1;

FIG. 4 is a fragmentary longitudinal sectional view showing a further modification of FIG. 1;

FIG. 5 is a fragmentary longitudinal sectional view showing the modification shown in FIG. 4 with the section being rotated by 90° about the longitudinal axis thereof;

FIG. 6 is a longitudinal sectional view partly broken away showing a second embodiment of the present invention;

FIG. 7 is a cross-sectional view taken along line VII-VII in FIG. 6;

FIG. 8 is a longitudinal sectional view partly broken away showing the embodiment of FIG. 6 with the section being rotated by 90° about the longitudinal axis thereof;

FIG. 9 is an end view showing the arrangement of the printing roller of FIG. 8;

FIG. 10 is a fragmentary longitudinal sectional view showing a modification of FIG. 8;

FIG. 11 is a fragmentary longitudinal sectional view showing a third embodiment of the device of the present invention; and

FIG. 12 is a fragmentary longitudinal sectional view showing a modification of FIG. 11.

DETAILED DESCRIPTION OF THE PREFERRED EMBODIMENTS

Referring now to FIG. 1 showing the first embodiment of the present invention, it comprises an elongated hollow holder 1 adapted to be gripped by the hand of an operator for the line drawing operation, a hollow connecting member 2 with its internal thread 2a threadedly engaged with the outer thread 1a of the holder 1, a applicator roller supporting member 4 with its internal thread 4a threadedly engaged with the outer thread 2b of the connecting member 2.

In accordance with the characteristic feature of the present invention, a cantilever shaft 3a is fixedly secured adjacent to the free end of the member 4 with the axis thereof oriented perpendicular to the longitudinal axis of the holder 1 as shown and a applicator roller 3 is rotatably mounted on the cantilever shaft 3a, and an ink tank 5 containing therein ink to be supplied and having an ink supplying portion 5a at its one end is freely shiftably located in the holder 1 with the ink supplying portion 5a passing through the connecting portion 2 and projecting therefrom through an opening in the member 4 so as to be adapted to contact with the periphery of the applicator roller 3 when the line drawing operation is to be effected. A cap 6 is fitted to the opposite end of the holder 1 so as to prevent the ink tank 5 from being withdrawn from the holder 1.

Thus, when the holder 1 is held by the end of an operator in the upstanding position with the applicator roller 3 positioned at the lowermost position and the applicator roller 3 is rollingly contacted with a sheet on which a line is to be drawn, the ink supplying portion 5a is slidingly contacted with the periphery of the applicator roller 3 with an appropriate contact pressure being held therebetween by virtue of the action of gravity of the ink tank 5 freely shiftably supported in the holder 1 thereby permitting an appropriate amount of ink to be

supplied from the ink supplying portion 5a of the ink tank 5 to the periphery of the applicator roller 3 so that an accurate line can be drawn on the sheet.

The line drawing operation using a rule can be greatly facilitated by the provision of the cantilever shaft 3a, because the rule can be conveniently contacted with the free end of the cantilever shaft 3a for drawing a line exactly in the desired position.

A flattened head 3b of enlarged diameter may be provided at the free end of the cantilever shaft 3a for more conveniently contacting the rule slidingly with the flattened head 3b of the cantilever shaft 3a.

The applicator roller 3 can be made detachable from the cantilever shaft 3a or it can be made detachable together with the cantilever shaft 3a from the member 4 or the applicator roller 3 can be detached from the connecting member 2 so that various forms of lines can be drawn by interchangeably mounting a selected printing roller of the desired form on the holder 1 as described previously.

The construction of the ink tank 5 and the ink supplying portion 5a should be varied depending upon the nature of the ink used, such as the kinds of dyestuffs and pigments used in the ink, the surface tension of the ink, the viscosity of the ink and the drying rate of the ink or the configuration of the applicator roller 3 in order to obtain the optimum condition of ink supplying operation. For example, in case the capillary action is utilized in the ink supplying portion 5a, the size of the capillary tube must be selected appropriately in conformance with the nature of the ink. Further, when a solid line is to be drawn, an ink supplying portion in the felt-like form is preferably used, whereas, when a broken line or a chain line is to be drawn, an ink supplying portion having a relatively hard or firm construction is preferred.

In the embodiment shown in FIG. 1, the end surface of the ink supplying portion 5a is flat and the periphery of the applicator roller 3 contacts tangentially with the end surface of the ink supplying portion 5a.

FIG. 3 shows a modification of FIG. 1. In FIG. 3, the connecting member 2' is secured to the holder 1 by the threaded engagement of the outer thread 2'a of the member 2' with the internal thread formed in the holder 1 and the axis of the cantilever shaft 3a is offset from the longitudinal axis of the holder 1. The flattened end surface of the ink supplying portion 5a of the ink tank 5 is enlarged so that the periphery of the applicator roller 3 sliding contacts tangentially with the flattened end surface of the ink supplying portion 5a. Since the axis of the applicator roller 3 is offset from longitudinal axis of the holder 1, the line drawing operation using a rule is facilitated by slidably contacting the flattened head 3b of the cantilever shaft 3a with the rule wherein the direction of movement of the applicator roller 3 with respect to the rule is so determined that the axis of the shaft 3a follows the longitudinal axis of the holder 1 during the guiding by the rule.

FIGS. 4 and 5 show a further modification of the device of FIG. 1. In this embodiment shown in FIGS. 3 and 4, the applicator roller supporting member 4' is slidably fitted around the connecting member 2'' threadedly engaging with the holder 1 and the member 4' is detachably secured to the connecting member 2' and, hence, to the holder 1 by the engagement of the flange 4'a of the member 4' with the internal flange 7a of a fastening member 7 threadedly engaging with the holder 1. In like manner as in the embodiment shown in

FIG. 3, the axis of the cantilever shaft 3a is offset from the longitudinal axis of the holder 1. However, in the embodiment shown in FIGS. 4 and 5, the end surface of the ink supplying portion 5'a is made in the conical shape and the periphery of the applicator roller 3 slidably contacts tangentially with the conical surface of the ink supplying portion 5'a thereby insuring an appropriate amount of ink to be supplied from the ink supplying portion 5'a to the periphery of the applicator roller 3 during the rolling contact thereof with a sheet on which a line is to be drawn.

The configuration of the end surface of the ink supplying portion of the ink tank 5 may be varied to any shape such as a concave spherical surface and a concave surface of any configuration insofar as the periphery of the applicator roller 3 tangentially contacts the end surface of the ink supplying portion of the ink tank during the rolling contact of the applicator roller with the sheet.

By the arrangement of the device as shown in FIGS. 1 to 5, the periphery of the applicator roller 3 is positively spaced from the ink supplying portion of the ink tank by maintaining the holder 1 in the inverted upright position with the applicator roller 3 held in the uppermost position when the device is not used thereby positively preventing ink from sticking to the periphery of the applicator roller 3, because the ink tank 5 moves apart from the applicator roller 3 by the action of gravity of the ink tank 5.

FIGS. 6-9 show the second embodiment of the present invention in which a rotatable ink roller 15 is interposed between the ink supplying portion 5a of the ink tank 5 and the applicator roller 3 in order to more uniformly supply ink to the periphery of the applicator roller 3.

As shown in FIGS. 6 and 8, an ink roller supporting member 13 is axially slidably fitted in the connecting member 12 which is threadedly secured to the holder 1 by the intermeshing threads 1a and 12a formed in the holder 1 and the member 12, respectively.

The applicator roller supporting member 16 has an arm 16a at one side thereof which rotatably mounts the cantilever shaft 3a of the applicator roller 3 and outer thread sections 16c at the other side opposite to the side at which the arm 16a is formed as shown in FIG. 7 which are separated by a hollow space 16b of the cross shape formed in the member 16 as seen in FIG. 7. The outer thread sections 16c are threadedly engaged with the internal thread 12c formed in the member 12 so as to be secured thereto. As seen in FIGS. 6, 7 and 8, the ink roller 15 and the shaft 15a thereof are received in the hollow space 16b of the cross shape formed in the member 16 during the threaded engagement of the member 16 with the member 12 wherein the member 13 supporting the shaft 15a of the ink roller 15 is rotated following the rotation of the member 16 thereby insuring the parallel relationship between the axis of the shaft 15a and the axis of the cantilever shaft 3a. Thus, the cantilever shaft 3a rotatably supporting the printing roller 3 is stationarily secured with respect to the holder 1 while the ink roller 15 is axially shiftable together with the member 13 in the connecting member 12.

A compression spring 14 is provided in the holder 1 and the connecting member 12 between the shoulder 1b of the holder 1 and the open end of the ink roller supporting member 13 as shown in FIG. 6 so that the member 13 is urged by the spring 14 axially of the

holder 1 together with the ink roller 15 toward the applicator roller 3 so that an appropriate rolling contact pressure is held between the roller 15 and the roller 3 thereby insuring an appropriate amount of ink to be uniformly supplied from the periphery of the roller 15 to the periphery of the roller 3 as the roller 3 rollingly contacts with a sheet for the line drawing operation.

In the similar manner as in the case of the embodiment shown in FIG. 1, the ink supplying portion 5a of the ink tank 5 is urged against the periphery of the ink roller 15 by the action of gravity of the ink tank 5 when the holder 1 is held in the upstanding position for the line drawing operation, thereby insuring an appropriate amount of ink to be supplied from the ink supplying portion 5a to the periphery of the roller 15.

When the holder 1 is held in the inverted upright position during the time the device is not used, the ink supplying portion 5a is held apart from the periphery of the ink roller 15 due to the action of gravity of the ink tank 5 thereby positively preventing ink from sticking on the periphery of the ink roller 15.

The axis of the applicator roller 3 may be offset from the longitudinal axis of the holder 1 in like manner as in the case of the embodiment of FIG. 3 so as to achieve the same effectiveness.

FIG. 10 shows a modification of the embodiment shown in FIG. 6. As shown therein, the cantilever shaft 3a of the applicator roller 3 is supported by an arm 12'd which is directly secured to the connecting member 12' and the ink roller supporting member 13 is slidably guided axially by the sliding engagement of a pin 22 fixed to the member 13 with an elongated axial slot 12'e formed in the member 12' so that the shaft 15a of the ink roller 15 is held in parallel relationship to the axis of the cantilever shaft 3a. The operation is similar to that shown in FIG. 6.

FIG. 11 shows the third embodiment of the present invention in which the applicator roller 3 is held apart from the ink roller 15 during the time the device is not used so that ink is prevented from sticking on the portions of the ink roller 15 and the applicator roller 3 at which they contact with each other. In this embodiment, the shaft 15a of the ink roller 15 is slidably supported in the elongated axial slots 12'f formed at the free end of the connecting member 12'' secured to the holder 1 in diametrically opposite relationship to each other so that the roller 15 is movable within a predetermined range as limited by the ends of the elongated slots 12'f, and the shaft 15a is urged by a spring 14' toward the applicator roller 3.

The applicator roller supporting member 16 is slidably fitted around the connecting member 12'' and axially guided by a pin 22 secured to the member 12'' which slidably engages within an elongated axial slot 12''e formed in the member 16' so that the shaft 3a is held in parallel to the shaft 15a. A sleeve 24 threadedly secured to the connecting member 12'' serves to limit the axial rightward movement of the member 16' to a predetermined range by the engagement of the shoulder 24a against the shoulder 16'c as shown in FIG. 11. A compression spring 23 is interposed between a shoulder formed in the member 12'' and a shoulder formed in the member 16' as shown so that the member 16' is urged axially so as to normally maintain the applicator roller 3 in spaced relationship from the ink roller 15.

In the line drawing operation, the applicator roller 3 is urged against a sheet and rollingly contacted with the sheet with the holder 1 held in upstanding position so

that the applicator roller 3 is axially moved against the action of the spring 23 so as to rollingly contact with the ink roller 15 under the contact pressure held therebetween by the action of the spring 14' thereby rotating the ink roller 15. Thus, the ink supplying portion 5a urged against the periphery of the ink roller 15 by the action of gravity of the ink tank 5 supplies ink onto the periphery of the ink roller 15 which in turn supplies ink uniformly onto the periphery of the applicator roller 3 thereby permitting a line to be drawn on the sheet.

FIG. 12 shows a modification of the embodiment of FIG. 11. In the embodiment shown in FIG. 12, the ink roller 15 is rotatably supported by the ink roller supporting member 13 in like manner as in the case of FIG. 10 and the member 13 is axially slidably fitted in the connecting member 12''' secured to the holder 1 but prevented from rotating relative to the connecting member 12''' by the engagement of the shaft 15a with the axial slots formed in the connecting member 12''' and urged by the spring 14 in like manner as in the case of FIG. 10. The applicator roller supporting member 16' is axially slidably fitted around the connecting member 2''' and urged by the spring 23' in like manner as in the case of FIG. 11 while the engagement of the pin 22 with the axial slot formed in the member 16' prevents the relative rotation of the member 16' with respect to the connecting member 12''' thereby maintaining the shaft 15a in parallel to the shaft 3a. The operation of the device of FIG. 12 is similar to that of FIG. 11.

In the embodiment shown in FIGS. 11 and 12, the ink roller 15 is shown as being axially shiftable with respect to the holder 1 and urged by the spring 14' or 14 toward the applicator roller 3. However, the shaft 15a of the ink roller 15 may be stationarily supported with respect to the holder 1 while permitting the rotation of the shaft 15a about its axis. In this case, the printing roller 3 is urged against the ink roller 15 during the line printing operation so as to rotate the ink roller 15 by the contact pressure given by the applicator roller 3 when a line is being drawn.

We claim:

1. In a device for drawing a line having an elongated hollow holder, an ink tank provided within said holder and having an ink supplying portion at its one end, a rotatable ink roller provided within said holder with its periphery being adapted to slidably contact with said ink supplying portion of said ink tank so as to be supplied with an appropriate amount of ink therefrom as said ink roller is rotated and an applicator roller rotatably supported at one end of said holder with its periphery being adapted to rollingly contact with the periphery of said ink roller so as to be supplied with an appropriate amount of ink from said ink roller for permitting a line to be drawn on a sheet as said applicator roller is rollingly contacted with said sheet to thereby rotate said ink roller, the improvement wherein said ink tank is freely shiftably located in said holder so that said ink supplying portion is urged against said ink roller by the

action of gravity of said ink tank when said holder is positioned in upstanding position for drawing a line with said applicator roller being located at lowermost position contacting said sheet, and said applicator roller is 5 rotatably supported by a cantilever shaft mounted on said one end of said holder thereby facilitating the line drawing operation, and wherein further, said ink roller is shiftably located within said holder in the direction of the longitudinal axis thereof, a single spring also being 10 provided within said holder so as to urge said ink roller in the longitudinal direction toward said applicator roller so as to thereby facilitate the maintenance of an appropriate amount of contact pressure between said ink roller and said applicator roller for transmitting an appropriate amount of ink from said ink roller to said applicator roller, while said ink supplying portion of said ink tank is also urged against said ink roller by the action of gravity of said ink tank during the line drawing operation, said ink tank, said ink roller, and said applicator roller being substantially aligned in the longitudinal direction of said holder.

2. Device for drawing a line according to claim 1, wherein said cantilever shaft of said applicator roller is stationarily mounted with respect to said holder.

3. Device for drawing a line according to claim 1, wherein said cantilever shaft is shiftably mounted with respect to said holder in the direction of the longitudinal axis thereof, another single spring also being provided within said holder for urging said cantilever shaft and said applicator roller away from said ink roller within a predetermined range so that said applicator roller is normally held apart from said ink roller, whereas, when said applicator roller is urged toward said ink roller against the biasing action of said another spring so as to be contacted therewith by rollingly contacting said applicator roller with said sheet for the line drawing operation with said holder held in said upstanding position, an appropriate contact pressure is held between said ink roller and said applicator roller by the action of said single spring so as to permit an appropriate amount of ink to be transmitted from said ink roller to said printing roller, while said ink supplying portion of said ink tank is urged against said ink roller by the action of gravity of said ink tank during the line drawing operation.

4. Device for drawing a line according to claim 1, wherein a flattened head of enlarged diameter is formed at the free end of said cantilever shaft facilitating the line drawing operation using a rule.

5. Device for drawing a line according to claim 1, wherein said applicator roller is detachably mounted on said holder thereby permitting various forms of lines to be drawn by interchangeably mounting a selected applicator roller of the desired form.

6. Device for drawing a line according to claim 1, wherein the axis of said cantilever shaft is offset from the longitudinal axis of said holder thereby facilitating the line drawing operation using a rule.
